United States Patent Office

Des. 217,878

Patented June 23, 1970

217,878

GOBLET OR SIMILAR ARTICLE

Fernando Alvarez, Glen Dale, W. Va., assignor to Morgantown Glassware Guild, Incorporated, Morgantown, W. Va.

Filed Feb. 28, 1969, Ser. No. 15,967

Term of patent 14 years

Int. Cl. D7—01

U.S. Cl. D36—8

Fig. 1

Fig. 2

Fig. 3

Fig. 4

FIG. 1 is a front elevational view of a goblet or similar article showing my new design;

FIG. 2 is a right side elevational view;

FIG. 3 is a top plan view;

FIG. 4 is a bottom plan view.

The characteristic feature of the design resides in the configuration of the pedestal portion.

I claim:

The ornamental design for a goblet or similar article, as shown and described.
